US00D753660S

(12) **United States Design Patent**
Zhou et al.

(10) **Patent No.:** **US D753,660 S**
(45) **Date of Patent:** **** Apr. 12, 2016**

(54) **INDICIA SCANNER**

(71) Applicant: **Hand Held Products, Inc.**, Fort Mill, SC (US)

(72) Inventors: **Peng Zhou**, Suzhou (CN); **Timothy R. Fitch**, Syracuse, NY (US); **Hao Xu**, Suzhou (CN)

(73) Assignee: **Hand Held Products, Inc.**, Fort Mill, SC (US)

(**) Term: **15 Years**

(21) Appl. No.: **29/532,816**

(22) Filed: **Jul. 10, 2015**

Related U.S. Application Data

(63) Continuation of application No. 29/492,903, filed on Jun. 4, 2014, now Pat. No. Des. 734,339.
